METHOD AND MEANS FOR PERFORMING ASSAYS

Joseph F. Pagano, Somerville, and Eugene V. Adams, Highland Park, N.J., assignors to Olin Mathieson Chemical Corporation, New York, N.Y., a corporation of Virginia

Filed Feb. 26, 1959, Ser. No. 795,688

10 Claims. (Cl. 195—103.5)

This invention relates to a device for assaying microorganisms.

Prior to this invention, circular paper discs impregnated with various chemotherapeutic agents have been used to determine the sensitivity spectrum of microorganisms. Thus, for example, to determine the antibiotic spectrum of a microorganism, the organism was grown in an agar-containing culture medium and a number of discs, each impregnated with a different antibiotic, were placed upon the medium. After a predetermined time, the sensitivity of the microorganism to a given antibiotic was determined by the zone of inhibition (clear area) around the discs.

The disadvantages of such procedure are manifest. Thus, the testing method required the careful placing of a plurality of discs on the nutrient medium; a time-consuming tedious procedure requiring the recordation of the contents and position of each disc. Furthermore, there is a common misconception in the art that the comparative activity of the impregnating substances is related to the diameter of the zone of inhibition or growth stimulation. In other words, the larger the zones, the greater the potency of a given substance, wherein fact quite often the area of the zone depended on non-pertinent physical characteristics of the impregnating substances, such as their relative diffusion rates through the agar medium.

It is an object of this invention, therefore, to provide a unitary simple device for assaying microorganisms, which is efficient to use.

It is another object of this invention to provide a device for assaying microorganisms which cannot be misread or misinterpreted.

It is still another object of this invention to provide a device for assaying microorganisms which is easily prepared commercially.

These objects are achieved by the device of this invention, which comprises a sheet of bibulous material having a plurality of spaced apertures therein, the portion of material peripheral to at least one aperture being impregnated with a microorganism-affecting substance. [By "microorganism-affecting substance" is meant a substance, such as an antibiotic, phage or assimilable carbon or nitrogen containing compound, which affects the growth pattern of at least one microorganism. This effect may be one of inhibition or enhancement and includes bacteriocidal, bacteriostatic, and nutrient substances.]

The device of this invention and its method of preparation and use are illustrated in the accompanying drawing, wherein:

Figure 1 is a top view of one embodiment of this invention;

Figure 2 is a perspective view of the device of this invention in place on a petri dish;

Figure 3 is a perspective view of a means for preparing the devices of this invention showing the impregnation of the devices with microorganism-affecting substances; and

2

Figure 4 is a sectional view taken through 4—4 of Figure 3.

Considering Figure 1 of the drawing, the device for assaying microorganisms of this invention comprises a sheet of bibulous material 1, such as porous paper (e.g. filter paper) having a plurality of spaced apertures 2, 3, 4, 5, and 6 therein. A portion of sheet 1 peripheral to at least one of the apertures is impregnated with a microorganism-affecting substance. In the device shown in Figure 1, portions of the sheet peripheral to apertures 3, 4, 5 and 6 are impregnated with different microorganism-affecting substances, such as different antibiotics. To aid in identifying which aperture is surrounded by a given material, the sheet is preferably provided with indica, as indicated by A, B, C, D, and E, adjacent to the respective apertures. Although the sheet and apertures shown in Figure 1 are circular in outline, these shapes are merely illustrative and rectangular or other shape sheets may be used. Furthermore, sheets containing apertures of different areas may also be used.

Figure 2 shows the devices of this invention in use. When so used, a petri dish 7 or other usual container is prepared with the usual agar-containing nutrient medium 8 and inoculated with the microorganism to be tested. Sheet 1 is then placed on top of the nutrient medium 8 and after a predetermined time the medium beneath apertures 2, 3, 4, 5 and 6 are observed. In this time, the microorganism-affecting substances surrounding the apertures has diffused into the area of the nutrient medium adjacent thereto including the area under the aperture. The effect of these substances on the microorganism being tested can then be determined by observing the growth pattern of the microorganism in the area under the aperture.

Thus, for example, to determine the mode of treatment of a pathogenic microorganism, a nutrient medium 8 in petri dish 7 is inoculated with the microorganism and the device of this invention is placed thereon. By way of illustration, the sheet 1 may contain an antifungal antibiotic, such as nystatin or amphotericin, on the portion peripheral to aperture 3; a broad-spectrum antibiotic, such as tetracycline or chlortetracycline, on the portion peripheral to aperture 4; and narrower spectrum antibiotics, such as streptomycin and penicillin on the portions peripheral to apertures 5 and 6, respectively. The portion peripheral to aperture 2 can remain untreated to act as a control. After a given time, the nutrient medium 8 is observed through the apertures. If a microorganism is present, it will be so indicated by a growth (cloudiness) in the nutrient medium under aperture 2. Assuming that a microorganism is present and is an antibiotic-sensitive fungus, such as *Candida albicans*, its nature will be shown by the lack of growth (clear area) under aperture 3, and growth (cloudiness) under apertures 2, 4, 5 and 6. In a similar manner, the sensitivity to antibiotics of a Gram-positive or Gram-negative bacteria can be determined.

Aside from the above use, the device of this invention can also be used to indicate the presence of a specific phage sensitive strain of microorganism by employing a sheet containing one or more apertures, the portions peripheral to each aperture containing a different phage. Furthermore, to indicate the growth pattern of a new microorganism, the microorganism can be grown in an agar medium deficient in a source of carbon and a sheet containing any number of potential sources of assimilable carbon can be placed thereon. Those carbon sources which will support the growth of the microorganism will then be shown by areas of growth (cloudiness) under the respective apertures.

The devices of this invention are readily prepared in sizable quantities by using the apparatus disclosed in Figures 3 and 4. A stock of sheets 1 are aligned so that

the apertures therein are in register. Bottom plate 9 is then positioned under the stack and top plate 10 is positioned on top of the stack. Threaded bolts 11 are then passed upwards through apertures 12 in bottom plate 9 and apertures 13 in top plate 10. The bolts are provided with heads 14 of sufficient size to prevent passage of the entire bolts through bottom plate 9. Wing nuts 15 are then screwed onto the free ends of the bolts thereby forcing the plates 9 and 10 together and compressing the stack of sheets 1 therebetween. The plates are so constructed and the apertures 12 and 13 therein so placed that the bolts pass outside the stack of sheets 1. Top plate 10 is provided with apertures 2', 3', 4', 5' and 6' in alignment with the apertures in sheets 1 and bottom plate 9 is preferably provided with indents, such as indents 4" and 5", also in alignment with the apertures in the top plate. The apertures in top plate 10, and sheets 1 and the indents in bottom plate 9 thereby provide a series of wells.

To prepare the devices of this invention, one or more of the wells are filled with a solution of the desired microorganism-affecting substances. After a time sufficient for absorption of some of the solution in the area of each sheet 1 peripheral to the well, excess solution is removed either by inverting the entire assembly or preferably siphoning off each excess solution separately thereby permitting reuse of the solution. The wing nuts are then removed and the plates separated. One or more of the sheets, after drying can then be packaged with a key indicating the treatment of each peripheral portion in a box or other suitable container.

The invention may be variously otherwise embodied within the scope of the appended claims.

What is claimed is:

1. A device for assaying microorganisms which comprises a sheet of bibulous material having a plurality of spaced apertures, the portions of material peripheral to at least two apertures being impregnated with different microorganism-affecting substances.
2. The device of claim 1 wherein the bibulous material is porous paper.

3. The device of claim 1 wherein the microorganism-affecting substances are antibiotics.

4. The device of claim 1 wherein the microorganism-affecting substances are phages.

5. The device of claim 1 wherein the microorganism-affecting substances are sources of assimilable carbon.

6. A device for assaying microorganisms, which comprises a circular sheet of porous paper having a plurality of spaced circular apertures therein, the portions of paper peripheral to at least two apertures being impregnated with different microorganism-affecting substances.

7. The device of claim 6 wherein the microorganism-affecting substances are antibiotics.

8. A method of assaying microorganisms, which comprises growing a microorganism on a nutrient medium upon which is positioned a sheet of bibulous material having a plurality of spaced apertures therein, the portions of material peripheral to at least two apertures and having been impregnated with different microorganism-affecting substances, and measuring the growth of the microorganism on the nutrient medium beneath said apertures.

9. A method of assaying microorganisms, which comprises growing a microorganism on a nutrient medium upon which is positioned a sheet of porous paper having a plurality of spaced apertures therein, at least two portions of the paper peripheral to different apertures having been impregnated with different microorganism-affecting substances, and comparing the extent of growth of the microorganism on the nutrient medium beneath said apertures.

10. The method of claim 9 wherein the microorganism-affecting substances are different antibiotics.
